UNITED STATES PATENT OFFICE.

JOHN KLASNICH AND JOHN J. ZWALSH, OF CLEVELAND, OHIO.

ELECTRIC-SIGN SWITCH.

Application filed July 29, 1922. Serial No. 578,397.

To all whom it may concern:

Be it known that we, JOHN KLASNICH and JOHN J. ZWALSH, citizens of the United States, residing at Cleveland, in the county of Cuyahoga and State of Ohio, have invented new and useful Improvements in Electric-Sign Switches, of which the following is a specification.

The object of our said invention is the provision of a switch designed more especially, but not necessarily, for electric signs and constructed with a view to materially economizing in the use of electric current and with a view to automatically operating in a reliable manner after it is adjusted to meet a particular condition.

To the attainment of the foregoing, the invention consists in the improvement as hereinafter described and definitely claimed.

20 In the accompanying drawings, forming part of this specification:—

Figure 1 is a front elevation of the switch mechanism constituting the best practical embodiment of our invention that we have 25 as yet devised.

Figure 2 is a vertical transverse section taken in the plane indicated by the line 2—2 of Figure 1.

Figure 3 is a section taken in the plane 30 indicated by the line 3—3 of Figure 1, looking downwardly.

Figures 4 and 5 are detail views herein-after explicitly referred to.

Figure 6 is a diagrammatic view illustrative of the electrical connections and arrangement.

Similar numerals of reference designate corresponding parts in all of the views of the drawings.

40 A plurality of incandescent electric lamps 1 and a switch 2 are arranged in parallel as will be readily understood by comparison of Figures 1 and 6, the lamps 1 being electrically connected together as designated by 45 3, and each lamp 1 being electrically connected by a lead 4 with an individual terminal 5^x. It will also be understood that one end lamp of the series is connected by a lead 5 with a positive pole of a source of

50 electric energy 6 and the other end lamp of the series is connected by a lead 7 with the winding of a solenoid 8. The said winding of the solenoid 8 is also connected by a lead 9 with a terminal 10 on a vertically swing-

55 ing lever 11, the said terminal 10 being opposed to a stationary terminal 12 connected

through a lead 13 with the positive pole of the source of energy 6. It will further be observed that a lead 14 electrically connects the lead 13 with a terminal 15 on a movable 60 switch member 16 which is fixed with respect to and is rotatable by a ratchet wheel 17. The said vertically swinging lever 11 is provided with upper and lower arms 18 and 19. Fulcrumed at 20 is a vertically swinging beam 21 the free end of which is disposed and movable between the said arms 18 and 19 of the lever 11. The said beam 21 is provided with a lateral projection 22 to engage the said arms 18 and 19, and carried by the said beam 21 is a pawl 23 to engage the teeth of the ratchet wheel 17. The said pawl 23 is yieldingly moved toward the ratchet wheel 17 by the gravitational action of the comparatively heavy arm 24 of the 75 pawl which pawl is pivoted to the beam at the point 25. Appropriately connected to and extending upwardly from the free end portion of the beam 21 is a rod 26 on which is the armature 27 of the solenoid 8 and 80 on which is also a piston 28, the said piston being movable in a cylinder 29 the upper portion of which is provided with a valved vent 30. Arranged on and in parallelism to the beam 21 is a threaded rod 31 on which is adjustable a heavy nut or weight 32. The piston 28 in combination with the cylinder 29 and the valved vent 30 are provided in order that the upward movement of the beam 21 can be readily regulated, i. e., retarded to a greater or less extent as conditions require. The heavy nut or weight 32 is provided in combination with the threaded rod 31 on which the nut is adjustable in 90 the direction of the length of the rod in 95 order to increase or diminish the gravitational capacity of the beam 21.

In the practical operation of our novel switch it will be manifest that with current supplied from the positive pole of the 100 source of energy through the lead 5, the series of lamps 1, the lamp connections 3 and the lead 5 to the winding of the solenoid 8, the beam 21 will be raised, and through the medium of the pawl 23 will rotate the ratchet wheel 17 and the sweep 16 in clockwise direction. As the beam 21 approaches the end of its upward movement, the lateral projection 22 by cooperation with the upper arm 18 moves the lever 11 and 110 thereby breaks the return connection from the solenoid winding to the source of

energy 6 by separating the terminal 10 from the terminal 12. At this time the switch member 16 is in contact with one of the stationary terminals 5*, and in consequence the 5 lamp 1 complementary to the said terminal 5* will be caused to glow, the return from the said lamp 1 being through the said terminal 5*, the terminal 15, and the leads 14 and 13 to the negative pole of the source 10 of energy. The said glowing of the said lamp will continue until the beam 21 gravitates sufficiently to enable the projection 22 by cooperation with the arm 19 to replace the terminal 10 in contact with the terminal 12. Under this latter condition, the lamp 15 circuit will be interrupted and the solenoid circuit will be again completed, whereby the 20 operation described will be repeated until the terminal 15 on the member 16 is in contact with the terminal 5* of the next succeeding lamp 1.

It will be manifest from the foregoing 25 that through the medium of our improvement only a minimum amount of current is employed, and it will also be manifest that we attain the said desired end through the medium of a simple and reliable mechanism and one well adapted to withstand the usage to which electric switch mechanism is ordinarily subjected.

We have entered into a detailed description 30 of the construction and relative arrangement of the parts embraced in the present and preferred embodiment of our invention in order to impart a full, clear and exact understanding of the said embodiment. We do not desire, however, to be understood as confining ourselves to the 35 said specific construction and relative arrangement of parts inasmuch as in the future practice of the invention various

changes and modifications may be made such as fall within the scope of our invention as defined in our appended claims.

Having described our invention, what we 45 claim and desire to secure by Letters-Patent, is:—

1. In an electric switch, the combination 50 of a solenoid, an armature comprised in said solenoid and having a piston movable with the armature, a cylinder receiving the said piston and having a valved vent, a ratchet wheel, a circular series of spaced terminals, a terminal movable step by step through the medium of the said ratchet 55 wheel, a vertically swinging beam having a lateral projection, a pawl carried by said beam for moving the ratchet wheel step by step, a terminal electrically connected with said spaced terminals, said movable terminal and said solenoid, and a vertically swinging lever electrically connected with the solenoid and having upper and lower arms to be engaged by said lateral projection of the 60 beam.

2. In an electric switch, the combination 65 of a stationary terminal, a vertically swinging lever having a terminal opposed to said stationary terminal and also having upper and lower spaced arms, a vertically swinging beam having a lateral projection for cooperation 70 with said arms of the vertically swinging lever, a solenoid for moving said beam, a terminal, means operated by the beam for moving said terminal, and spaced 75 terminals for cooperation with said movable terminal.

In testimony whereof we affix our signatures.

JOHN KLASNICH.
JOHN J. ZWALSH.
